JOINT FOR RAIL ENDS AND SPLICE BARS
THEREFORRichard F. Greenwood, New York, N. Y., assignor
to Standard Equipments, Inc., a corporation of
Maryland

Application August 22, 1932, Serial No. 629,814

2 Claims. (Cl. 238—243)

This invention relates to improvements in joints for rail ends and splice bars therefor.

It has been determined that the apex of the strain of the rolling load on a rail occurs in a vertical plane extending longitudinally about an inch from the center line or middle of the rail-head and parallel with and closely adjacent to the web of the rail, and it is one of the objects of this invention to utilize my splice bar to assist the railhead in supporting this load-strain more effectively by providing a bar which will engage beneath the head in the plane of the load-strain and by positioning the body or web of such bar in a position beneath the head which will substantially coincide with the plane of such load-strain, and with this end in view, I provide for contact of the bar preferably with the entire fishing area of the rail including the rail-web and upper and lower fillet portions between the web and the head and flange respectively, and the areas outside of the said upper and lower fillet portions.

Still another object of my invention is to provide integrally in a splice bar, a nut-lock spring washer adapted to enable the tight retention of nuts on the bolts, and to eliminate the use of loose, independent nut-lock washers and the expense incident thereto.

Still another object of my invention is to provide a splice bar having its middle portion contacting with the fishing area of the rail-ends including the web, upper and lower fillets and flange and head sections, and also to provide a bar having end portions similarly contacting with the said entire fishing area of the rail ends and particularly with the web section of such fishing area.

Still another object of my invention is to utilize a splice-bar construction having a web section contacting with and bearing on the web section of the fishing area of the rail and provided with an integral localized section struck-up and so formed as to be relieved from said web contacting section and surrounding one or more bolt holes to produce integrally from the metal of the bar a nut-lock element spaced or relieved from contact with the said web and adapted to yield sufficiently to pressure by the nut and bolt on the bars to cause the nuts when screwed home on the bolts to be securely locked on the bars by the spring action or effect of the integral struck-up portion.

With these and other objects in view, the invention comprises the combination of members and arrangement of parts so combined as to

co-act and co-operate with each other in the performance of the functions and the accomplishment of the results herein contemplated, and comprises in one of its adaptions the species or preferred form illustrated in the accompanying drawing, in which:

Fig. 1 is a view in elevation of one side of a rail joint embodying my invention;

Fig. 2 is a vertical section on the line 2—2 of Fig. 1 looking in the direction of the arrows and showing the bolt before the nut is tightened up on the bolt;

Fig. 3 is a section similar to Fig. 2 showing the nut tightened up on the bolt;

Fig. 4 is a section on the line 4—4 of Fig. 1 looking in the direction of the arrows;

Fig. 5 is a horizontal section on the line 5—5 of Fig. 1 looking in the direction of the arrows;

Fig. 6 is a view in elevation similar to Fig. 1 showing a modified form of my invention;

Fig. 7 is a section on the line 7—7 of Fig. 6 looking in the direction of the arrows.

Referring now to this drawing, it will be seen that one feature of my invention is directed to a joint structure in which the web or body of the splice bars will be disposed vertically beneath the sides of the head of the rail so as to provide a support and to reinforce said head directly in the plane through which the major portion or apex of the stress of the load of rolling stock on said rail is transmitted and which plane is estimated to be removed about one inch from the middle of the head of the rail, known as the vertical centroid and also to provide a joint in which the inner surface of the splice bars have a contact area engaging with a major portion of the fishing area of the rail including a contact between the web of the bar and the web-section of said fishing area of the rail and preferably also with the head and flange fillets and with surfaces beneath the rail head and with the flange throughout its entire length except where struck up sections prevail as shown.

Referring now particularly to Figs. 1 to 5 of this drawing, 10—10' indicates rail ends joined together by splice bars 11—11'. In said Figs. 1 to 5 inclusive, each of the splice bars is provided with a web section 12 and preferably with a top-contacting flange 13 contacting with the under surface 14 of the head and fillet 15 between the head and web 16 of the rail which I shall hereinafter call "the head fillet" and said bar also is provided with a bottom flange 17 contacting with the rail flange 18 and with the lower fillet 19

between the rail-web and rail-flange, which fillet I shall hereinafter call the "flange fillet".

As illustrated, the web 12 of each of the splice bars has its middle section 12' which bridges the joint disposed in contact with the web portion 16 of the fishing area of the rail and the end sections 12a and 12b at the outer sides of the bolts of the splice bars also have their web portions contacting with the web portion of the rail, and in the preferred embodiment of my invention shown in Figs. 1 to 5, the web portion 12c and 12d also contact with the web portion of the rails as more particularly shown in Fig. 5. In the construction shown in Figs. 1 to 5 therefore, the splice bars 15 will have contact with the fishing area, including the web of the rail, the under surfaces of the rail head, the head-fillets, the top surface of the rail-flange and the flange fillet, said bar being substantially U shaped in cross-section and disposed oppositely to the rail joint design employed in general practice. When a bar is fitted in this position, the web or body of the bar will reinforce the head and web of the rail and will be disposed vertically beneath the plane in the head through 25 which the major portion of the strain of the load is transmitted during the movement of the rolling stock of the rails in the cycle of positive and negative stress values.

My invention is also directed to the formation integrally in the web portion of a splice bar of a nut-lock washer section localized in said web section so as to surround a bolt hole or bolt holes, whereby independent spring nut-lock washers 30 may be eliminated and the nuts and bolts will be held securely by the spring tension afforded in the localized metal portion constituting said lockwasher section.

Also in accordance with my invention, the splice bars are made of high carbon spring metal 40 and an integral portion 20 surrounding each bolt-hole is struck up from the web of the bar so as to provide an integral spring-washer section, the inner surface of which will be slightly spaced from the normal plane of the inner surface of the bar and will be relieved from contact with the rail-web and the outer surface of which will be slightly raised above the normal plane of the outer surface of the bar, and when a pair of these splice bars are positioned as hereinabove 45 described and shown in the drawing, the said outer surfaces will be contacted directly by the bolt head and the nut 22.

The metal of the bar will be of such resilience as to enable the integral washer to have sufficient 50 springiness or resilience to permit a slight inward springing-movement thereof upon pressure caused by the tightening of the bolts. These integral struck-up washers will thus, under the screw pressure due to tightening up of the nuts 55 on the bolts, resiliently hold and lock the nuts securely in position on the bolts.

Figs. 6 and 7 show a construction which is in all respects similar to that shown in Figs. 1 to 5 except that a single struck-up integral spring washer, instead of surrounding one bolt-hole only, is arranged to include a plurality of bolt holes so that one integral spring washer includes and serves a plurality of bolts, or it may be said 60 that a plurality of integral spring-washers are connected together in one struck up portion. In this construction, however, the web of the bar is arranged to provide contact with the web section of the fishing area of the rail at a plurality of

points along its length and preferably has such contact at the middle section 12' and at the ends of the splice bars on opposite sides of the bolt holes. In this way, effective contact is provided between the rail webs and the inner surfaces of the webs of the splice bars to provide a bearing contact for applying pressure to the spring washer portions and also contact is maintained with the major portion of the fishing area of the rail, preferably including contact with the rail-web 10 section, the head and flange fillets and head and flange fishing sections outside of the said fillets. 5

Having described my invention, I claim:—

1. In a rail-joint, a pair of rail ends having bolt holes, a pair of splice bars of channel-formation, each having across the joint and at opposite ends web-sections contacting throughout their entire surfaces with the web-sections of the fishing areas of the rail ends and other web-sections contacting at one portion and offset at another portion of their surfaces with said web-section of the fishing areas of the rails, said bars also having outwardly-extending flanges comprising a top-flange contacting with the head-fillet and under surface of the head of the rail and a bottom flange contacting with the flange-fillet and with a portion of the flange of the rail, the major portion of the metal of the splice bars being disposed beneath the overhanging head portions of the rail in longitudinal-vertical parallel planes 30 extending closely adjacent to the web of the rail and one of said planes being closely adjacent to the vertical plane through which the major portion of the strain of the load is transmitted, whereby greater strength of the joint is produced 35 and offset portions are provided for locking the bar, bolt holes in said offset portions, and bolts passing through the bolt holes of said bars and rail ends.

2. In a rail-joint, a pair of rail ends having bolt holes, a pair of splice bars of channel-formation, each having bolt holes registering with the bolt holes of the rail ends and provided across the joint, at opposite ends and between the bolt holes with web-sections contacting throughout their entire surfaces with the web-section of the fishing area of the rail ends and also provided with web-sections having portions adjacent to the bolt holes offset from said web-section and other portions surrounding said offset portions 45 in contact with the fishing area of the rail, said offset portions of said web-sections of the splice-bars comprising localized portions surrounding the bolt holes and struck up in relief from the normal plane of the web of the bar to provide integral spring-washers, said splice bars also having outwardly extending flanges comprising a top-flange contacting with the head-fillet and under surface of the head of the rail and a bottom flange contacting with the flange-fillet and with a portion of the flange of the rail, the major portion of the metal of the splice bar being disposed beneath the overhanging head portions of the rail in longitudinal-vertical parallel planes 55 extending closely adjacent to the web of the rail and one of said planes being closely adjacent to the vertical plane through which the major portion of the strain of the load is transmitted whereby greater strength of the joint is produced 60 and localized washer portions are provided for locking the bar.

RICHARD F. GREENWOOD.
